UNITED STATES PATENT OFFICE.

JOHN M. SAUDER, OF HARRISBURG, PENNSYLVANIA.

METALLIC SPRING FOR SUSPENDERS, &c.

SPECIFICATION forming part of Letters Patent No. 349,904, dated September 28, 1886.

Application filed April 22, 1886. Serial No. 199,859. (No model.)

To all whom it may concern:

Be it known that I, JOHN M. SAUDER, of Harrisburg, in the county of Dauphin and State of Pennsylvania, have invented a new and useful Improvement in Metallic Springs for Suspenders and other Uses, of which the following is a full, clear, and exact description.

The drawing represents a front elevation of my improved spring shown as applied to a suspender.

My invention consists in the construction and arrangement of parts, as will be herein-after fully described and claimed.

The spring is formed of wire bent to form two parallel series of flat loops, A A, the loops of the two series being bent in opposite directions and connected at their opposite ends by means of the cross-wires B D, which form the securing or attaching loops.

C represents the shoulder-strap secured to loop B, and F represents the ends or button-pieces, having a hook, E, connected to the loop D.

Having thus described my invention, what I claim as new, and desire to secure by Letters Patent, is—

As an improved article of manufacture, a spring of the character described, formed of two parallel series of flat loops and cross-pieces connecting said loops at their opposite ends and forming securing or attaching loops, substantially as set forth.

JOHN M. SAUDER.
